UNITED STATES PATENT OFFICE.

JOHN E. WALSH, OF NEW YORK, N. Y.

COALING VESSEL.

SPECIFICATION forming part of Letters Patent No. 623,268, dated April 18, 1899.

Application filed May 24, 1898. Serial No. 681,613. (No model.)

To all whom it may concern:

Be it known that I, JOHN E. WALSH, a citizen of the United States, residing at New York, in the county of New York and State of New York, have invented certain new and useful Improvements in Coaling Vessels, of which the following is a specification, reference being had therein to the accompanying drawings.

10 This invention relates to improvements in coaling vessels; and the invention consists in a combination of devices, hereinafter described, by means of which sea-going vessels can be coaled while at sea towing a lighter or 15 storage vessel fitted out for expeditious handling of coal.

In the accompanying drawings, Figure 1 represents a side elevation of the improved 20 coal-storage vessel and its coal-handling devices in tow of a vessel to be coaled, and Fig. 2 is a front elevation of the coal-storage vessel.

Upon a vessel A, having, preferably, four 25 separate departments in its hold for the separate storage of different sizes of coal, are mounted, preferably, two masts M M', one between each pair of hatches and provided each with two booms b b, running longitudinally in opposite directions, one over each adjoining hatch. Each boom carries its trolley 30 and traveling gear, worked, preferably, from a hoisting-engine, and serves to hoist the coal from the hold, preferably in buckets, either to the deck of the vessel A or to small platforms P P', secured one to each mast of vessel A. Near the top of each mast is secured 35 a cross-piece C C', and from each end of these cross-pieces is suspended a pair of pulley-blocks O O', the outer ends of the falls or ropes R R' of which are either connected with a trolley or secured to the front mast M of the vessel A or to the rear mast of the vessel to be coaled in a slanting position, as shown in Fig. 1 of the drawings. Trolleys t t' are mounted upon each of these guide-ropes and serve 40 to carry the coal in buckets or otherwise from the front mast M of vessel A to the vessel to be coaled or from the rear to the front mast of the vessel A. A weight W, suspended from a lower pulley-block O, holds the guide-rope R in tension, while the rope R' is stretched 45 permanently in a slanting position between

the masts M and M', as shown in Fig. 1 of the drawings. To the lower pulley-blocks, carrying the rope leading to the rear end of the trolleys, strong ropes a a', connected with drums 55 F F' of hoisting-engines, are secured and serve to guide the safe descent of the trolleys t t', with their freight, and to return these trolleys with the empty coal-buckets suspended therefrom. The platform P' on the rear mast is 60 placed higher than the platform P on the front mast, and both platforms serve to support one or more attendants, who receive thereon the load from the hold of vessel A and transfer it to hooks suspended from the trolleys. 65

Auxiliary booms d d' are secured near the top of each mast for the speedy handling of the coal and its safe transfer from a platform to a trolley-hook.

In operating this invention the rope R is 70 passed on board of the ship to be coaled and there secured at the proper height above deck. The speed of the vessels in motion is held to be sufficient to keep the rope R taut. All the coal from the front hatches can now be transferred by the aid of the rope R, trolley t, and then the stern departments must be unloaded, 75 which is effected by the aid of the rope R' and trolley t' in addition to the rope R and trolley t. With one man on each platform and 80 several below a very economical and speedy transfer of coal from one vessel to the other can be effected while a vessel is going to sea, the rigging of the rope R and its trolley requiring but little time. 85

Having thus described my invention, I claim—

1. In a coal-lighter the combination of a hull A, masts M M' having cross-pieces C C' platforms P P' and booms b b', a rope R having 90 one end secured to and passing through pulley-blocks O O' suspended from said cross-piece C and carrying a weight W, and the other end being adapted to be secured to another vessel, a rope R' secured between said masts 95 M M', trolleys t t' running upon said ropes R R' and operated by means of hoisting tackle and engines, as and for the purposes herein shown and described.

2. In a coal-lighter the combination of a hull 100 A masts M M' having cross-pieces C C' platforms P P', booms b b' and d d', a rope R, hav-

ing one end secured to and passing through pulley-blocks O O' suspended from said cross-piece C and carrying a weight W and the other end being adapted to be secured to another vessel, a rope R' secured between said masts M M' trolleys t t' running upon said ropes R R' and operated by means of hoisting-tackle suspended from said cross-pieces C C' and by means of ropes a a' wound upon drums F F'

of hoisting-engines, as and for the purposes to herein shown and set forth.

In testimony whereof I affix my signature in presence of two witnesses.

JOHN E. WALSH.
